UNITED STATES PATENT OFFICE.

JOHN SELLERS BANCROFT AND MAURITZ C. INDAHL, OF PHILADELPHIA, PENNSYLVANIA, ASSIGNORS TO LANSTON MONOTYPE MACHINE COMPANY, OF PHILADELPHIA, PENNSYLVANIA, A CORPORATION OF VIRGINIA.

GALLEY MECHANISM FOR TYPE-COMPOSING MACHINES.

1,172,251.

Specification of Letters Patent. Patented Feb. 22, 1916.

Application filed March 12, 1914. Serial No. 824,179.

To all whom it may concern:

Be it known that we, JOHN SELLERS BANCROFT and MAURITZ C. INDAHL, citizens of the United States, residing at Philadelphia, 5 in the county of Philadelphia and State of Pennsylvania, have invented certain new and useful Improvements in Galley Mechanism for Type-Composing Machines; and we do hereby declare the following to be a full, 10 clear, and exact description of the same, reference being had to the accompanying drawings, forming part of this specification, and to the figures and letters of reference marked thereon.

15 This invention relates to galley mechanism of the kind used in connection with signal controlled automatic type casting and composing machines for assembling the type, as delivered, into lines and the lines into columns in a galley. Each line after it is set up in the assembling channel is moved by a carrier engaging the last inserted type and operating against the resistance of a movable type support at the opposite end of the 20 line, to bring one end of the latter into register with one wall of the galley entrance. In commercial machines of this class the performing members of the galley mechanism remain at rest while the type for a line 25 are being assembled, and they are connected up with their driver by mechanism responding to signals contained in the controlling record strip and occurring between successive series of signals representing the types 30 of adjacent lines. In such cases the measure of the line becomes in effect a component of the record strip or controller, inasmuch as it has to be taken into consideration in composing the matter for each line, to the 35 end that the aggregate space occupied by the represented type shall equal the measure, the galley mechanism being provided with a trip wherebv a too long or too short line is made operative to arrest the machine. In 40 commercial machines of this class the justification signal, located between the associated type signals representing contiguous lines 45 of matter, is utilized for starting the galley mechanism in motion to dispose of the previously assembled line of type, and in the 50 absence of such a starting signal, as when setting up sorts or similar matter not requiring justification or more than a single

indicating signal, recourse must be had to manually operated starting devices if it is 55 desired to deliver the type into the galley.

Now the object of the present invention is to enable the galley mechanism to be set to produce any length of line within its capacity, automatically and independently of 60 the record strip, and this is accomplished by placing the starting devices of the galley mechanism under the direct control of the line as assembled, so that when, by the addition of successive type thereto, the line 65 has reached the desired dimensions it will operate to automatically start the galley mechanism into action and thus effect a transfer of the operating line into the galley. 70

In the accompanying drawings illustrating a preferred form of embodiment of the invention, Figure 1 is a top plan view of a galley mechanism equipped with the line actuated tripping devices. Fig. 2 is a front 75 elevation. Fig. 3 is a top plan view, on an enlarged scale, of the tripping devices. Fig. 4 is a perspective view of a part of the bracket to which the tripping devices are applied. Fig. 5 is a perspective view of the 80 galley trip lever showing the added connections for coupling up the line trips. Fig. 6 is a perspective view of the type support and trip extension.

Like numerals designate the same parts 85 in the several figures.

The invention is illustrated as applied to the galley mechanism of Patent No. 674,375, dated May 21, 1901, and it will suffice for present purposes to designate some of the 90 elements reproduced from said patent such as the type assembling or line channel 1 provided with sustaining jaws at the entrance end and continuing outward therefrom between the horizontally movable line trans- 95 ferrer 2 and the vertically movable galley blade 3, the latter located at the entrance to the galley 4. The adjustable wall 5 of the galley is connected at one end to the adjustable support 6 of the trip 7. Mounted 100 to slide in ways on the line transerrer is the type support 8, and traversing longitudinally of the line channel is the line carrier 9.

The actuating devices controlling and effecting, in timed relation, the movements of 105 the performing member, i. e., line carrier,

galley blade and line transerrer, are connected to the driving shaft 10 through a one revolution clutch 11 under the control of a trip lever 12, the latter in turn controlled by a signal in the record strip, to start the galley in operation and discharge the assembled line into the galley.

The sequence of operation performed by the galley mechanism as thus composed is as follows: After the signals representing individual types for a line have operated, a separate signal in the record strip or the justification signal preceding the signals for the next line, operates through appropriate mechanism (not shown) to actuate trip lever 12 in a manner to permit the closing of clutch 11 during one revolution only of driving shaft 10. Line carrier 9 is thereupon moved by its actuating lever 13 to a position in rear of the last type of the line and is then moved outward along the line channel until brought opposite the inner edge of the galley entrance, where its further outward motion is arrested. Galley blade 8 is next elevated to uncover the galley entrance and the line transerrer is advanced to shift the line from the line channel into the galley, after which it is retracted to first position and the galley blade lowered. The line carrier is withdrawn laterally from the line channel and then returned to initial position, and while so doing a latch 14 located outside the type support 8 engages the latter to return it to initial position near the entrance to the line channel, and is then slightly withdrawn, whereupon lever 12 is reengaged to open the clutch and the cycle is completed. While admirably adapted for composing to measure in justified lines this mechanism is found deficient in some respects for disposing of sorts and like matter in the production of which no galley operating signal is employed, and when, as is not infrequently the case, it is desired to produce a number of types bearing the same character by the simple expedient of arresting the feed of the record strip with the signal corresponding to the desired type in operative position.

It is proposed, therefore, according to the present invention, to supply an auxiliary trip mechanism, one interchangeable in use with the signal controlled devices but operated by the line as assembled to actuate the clutch and thus measure the produced line. In the preferred form illustrated this auxiliary trip mechanism includes a motor device coupled with the clutch closing member of the driving mechanism, a latch for restraining or suspending the action of said motor, latch actuating means coupled and moving with the type support and operating, when the desired length of line is attained, to release or set in action the motor and thus start the galley mechanism in ac-

tion, and means for automatically retracting the motor device and reengaging its controlling latch.

In the present embodiment there is erected upon the frame a bracket 15, to the upper section of which is pivotally attached a lever or latch 16, the upper arm whereof extends above and parallel with the line engaging section of said transerrer. Supported at one end in bracket 15 and at the other in a coupling 17 detachably secured to lever 12, is a rod 18 against which engages the lower arm of lever 16. Interposed between an adjustable head 19 carried by rod 18 and the side of bracket 15 is a motor spring 20 tending at all times to move rod 18 in a direction to effect the withdrawal of lever 12 and the consequent closing of the clutch, but normally prevented from so doing by the engagement of lever 16 with a collar 21 on rod 18. The arrangement is such that when lever 16 is tilted to withdraw its lever arm from engagement with collar 21 the motor devices represented by rod 18 and spring 20 will immediately shift lever 12 to release and close clutch 11 thereby starting the galley mechanism in action. The movement of lever 16 for effecting the closing of the clutch is controlled from the line through the agency of a slide 22 detachably coupled with the type support 8 and movable therewith in a guide way on the line transerrer. Slide 22 carries a head 23 in position to engage a head 24 the latter secured to lever 16 in a manner to permit adjustment in a direction longitudinally of the line channel. The arrangement is such that as the line is built up by the addition of successive type and the type support correspondingly moved outward in the line channel, head 23 of slide 22 will be caused to engage head 24 on lever 16 thereby tilting the latter until it passes off collar 21, thereby setting in action the mechanism for closing the clutch and starting the galley mechanism in action to engage the last type delivered and remove the line of which it forms one terminal. The length of the line is regulated and determined by the relative positions of heads 23 and 24. The return of rod 18 to initial position to permit lever 12 to resume its engaging position is automatically effected in timed relation through the agency of a pin or shoulder 25 on actuating lever 13, said pin engaging a bearing 27 coupled with rod 18. This engagement takes place at or near the end of the inward stroke of lever 13 and after type support 8 has been engaged to withdraw head 23 from contact with head 24, thus permitting reengagement of lever 16 with collar 21 when lever 13 shall make its initial stroke to release the type support.

As herein shown the auxiliary trip mechanism is specially designed for application to existing commercial machines and without

interference with the normal or signal actuating capacities and functions, to which ends the slide 22 with its actuating head 23 is detachably connected to the usual type support 8 and arranged to be received in the same guides; and, further, the connection between operating rod 18 and the clutch controlling lever 12 is made through a coupling 17 the latter detachably applied to the power end of lever 12 and adopted to move the lever only in one direction. Pivotally and detachably mounted upon the pivot of lever 12 is a plate or arm 27 whose outer or free end extends into the path of pin 25 carried by lever 13. To plate 27 is pivotally attached the coupling 17, the latter provided with two dependent members of which one, 28, receives the end of rod 18 and the other, 29, extends down in rear of lever 12 and is provided with a shoulder or bearing 30 resting upon said lever.

The points of connection between coupling 17 and plate 27 and rod 18 are in line, so that the pressure of pin 25 on plate 27 tends to draw rod 18 inward against the pressure of its actuating spring for effecting the reengagement of lever 16, during which movement coupling 17 moves independently of lever 12, which latter is thus left to the control of its retracting spring 31 and subject to the action of the usual signal controlled automatic actuating devices contacting with the power end of lever 12, as usual.

While the detachable connection between the slide 22 and type support 8 may be of any usual character, it is preferably formed by interlocking hooks 40 and 41 on the ends of the respective members, as shown in Fig. 6.

Having thus described our invention, what we claim as new and desire to secure by Letters Patent of the United States is,—

1. A galley mechanism for type composing machines equipped with signal controlled starting means and in combination therewith, an auxiliary line-controlled actuating means coupled with said signal controlled starting means.

2. In a galley mechanism, and in combination with the starting member thereof, line controlled actuating devices for said member including a member movable with the line, actuating devices for said starting member, and a restraining latch therefor, said restraining latch being controlled by the member responding to the movements of the line.

3. A galley mechanism provided with a line assembling channel, a line carrier and a type support movable longitudinally of said channel, and actuating devices including a starting member, and in combination therewith, actuating means coupled with said starting member, releasing or control devices for said actuating means, and means

coupled with the type support and acting upon said releasing devices at a predetermined point in the path of movement of the type support to effect the starting in action of the galley mechanism.

4. A galley mechanism provided with a line assembling channel, a type support movable in said channel, a line carrier movable longitudinally of the channel, and actuating devices for said carrier including driving and driven members and a one revolution clutch with a clutch closing member, and in combination therewith, a line controlled actuating mechanism coupled with said clutch closing member.

5. A galley mechanism embodying a line assembling channel, a type support, a reciprocatory line carrier and actuating mechanism therefor including a one revolution clutch with a starter therefor, and in combination therewith, a line controlled actuating mechanism for said starter, the same including a member coupled to move in unison with the type support, an actuating mechanism coupled with the starter for the clutch, a restraining latch for said starter actuating mechanism, and actuating devices intermediate the member coupled with the type support and the latch for retracting the latter.

6. A galley mechanism equipped with a line assembling channel, a line carrier movable longitudinally of said channel, a movable type support opposing the line carrier and actuating devices for the line carrier including a reciprocatory member and driving mechanism containing a clutch and a controlling member therefor, and in combination therewith, a line controlled actuating mechanism for said clutch controlling member including a motor, a restraining latch and means coupled with the type support for actuating said latch.

7. A galley mechanism equipped with a line assembling channel, a line carrier and an opposed type support movable in said channel, and actuating mechanism for the line carrier including a driving clutch and controlling means therefor, and in combination therewith a line controlled actuating mechanism for said clutch controlling means the same including motor devices, a restraining latch, means coupled with the type support for actuating said latch, and means coupled with the line carrier actuating mechanism for automatically retracting the motor devices.

8. An auxiliary line-actuated trip mechanism for the driving clutch of a galley mechanism such as described, the same including a slide adapted for application to the line transerrer in the guide for the type support and for detachable connection with the latter, a rod adapted to be coupled with the clutch closing member and provided with a

motor spring and a detent or collar, and a latch mounted in position to engage said detent or collar, said latch being provided with an adjustable abutment for engaging the aforesaid slide.

9. A galley mechanism provided with a line assembling channel, opposed movable galley blade and line transfeerer forming opposite walls of said channel, a line carrier and opposed type support movable longitudinally of said channel and a driving mechanism including an actuating lever for the line carrier and a one revolution clutch with a controlling member, and in combination therewith, a line actuated trip mechanism for said clutch controlling member, the same including a rod arranged in proximity to the line transfeerer and coupled with said clutch controlling member, a motor spring for said rod, a latch engaging a shoulder on the rod, said latch provided with an abutment adjustable longitudinally of the line channel, a slide carried by the line transfeerer in position to engage

the type support and the latch abutment, and an abutment carried by the line carrier actuating lever in position to engage a part coupled with said rod to retract the latter, compress the motor spring and reengage the latch.

10. In a monotype casting machine, the combination with a frame having a type channel, a galley cam, a trip lever, a driving shaft, a clutch between the driving shaft and the galley cam controlled by the trip lever, a line hook actuated by the galley cam and a column pusher actuated by the galley cam, of a device connected with the trip lever embodying a member arranged in the path of the type channel and actuated by the movement of the type in the type channel to actuate the trip lever and inaugurate the movement of the column pusher.
